CLAIM

The ornamental design for a toner case for electrophotographic copier, as shown and described.

DESCRIPTION

FIG. 1 is a front elevational view of a toner case for an electrophotographic copier showing my new design, the rear elevational view being a mirror image thereof; FIG. 2 is a top plan view thereof; FIG. 3 is a bottom plan view thereof; and FIG. 4 is a right side elevational view thereof, the left side elevational view being a mirror image thereof.
